UNITED STATES PATENT OFFICE.

GABRIEL J. KRAVAC, OF MELCHER, IOWA.

EXTENSION-LADDER.

1,171,793.

Specification of Letters Patent. Patented Feb. 15, 1916.

Application filed July 30, 1915. Serial No. 42,842.

To all whom it may concern:

Be it known that I, GABRIEL J. KRAVAC, a citizen of the United States, residing at Melcher, in the county of Marion, State of 5 Iowa, have invented certain new and useful Improvements in Extension-Ladders; and I do hereby declare the following to be a full, clear, and exact description of the invention, such as will enable others skilled 10 in the art to which it appertains to make and use the same.

This invention relates to improvements in ladders, and particularly to extension ladders.

15 One object of the present invention is to provide an extension ladder which is simple and cheap in construction, and which is durable and effective in use.

Another object of the invention is to provide 20 an extension ladder which can be quickly and easily extended and collapsed, and which will occupy a minimum amount of space when so collapsed.

Another object of the invention resides 25 in the novel means for extending and collapsing the ladder.

Other objects and advantages will be apparent from the following description when taken in connection with the accompanying drawing.

In the drawing: Figure 1 is a front elevation of my improved ladder in extended position. Fig. 2 is a side elevation of the same in the position of Fig. 1. Fig. 3 is a 35 side elevation of the ladder in collapsed or folded position. Fig. 4 is a horizontal sectional view on the line 4—4 of Fig. 2. Fig. 5 is a longitudinal sectional view on the line 5—5 of Fig. 4. Fig. 6 is a transverse sectional view on the line 6—6 of Fig. 4.

Referring particularly to the accompanying drawing, 10 represents a box or casing which is adapted to be mounted on a horse or motor-drawn vehicle. Mounted in the 45 casing, and extending longitudinally thereon, is an oppositely threaded screw shaft 11, one end of which is provided with a crank handle 12 for rotating the shaft. A pair of blocks 13 and 14 are disposed in the ends 50 of the casing, and are provided with interiorly threaded openings 15 through which the oppositely threaded portions of the screw shaft passes. Thus, by turning the crank handle the shaft will be rotated 55 to move the blocks toward and away from

each other. Each of the blocks carries a pair of vertically extending apertured ears 16, and pivotally connected to each of these ears is the lower end of one of the links 17 of a lazy tongs 18. From an inspection of 60 the drawing, it will be seen that there are two of these lazy tongs 18, the same being arranged in parallel relation. Extending through the inner joints of the links of the lazy tongs, and forming the pivots thereof, 65 are the ends of the steps or rungs 19.

Connected to the upper ends of the lazy tongs is a box 21, in which the person, or persons, mounting the ladder can seat or stand themselves, while manipulating any 70 mechanism or apparatus, such as fire hose, or tools used in repairing trolley or other overhead wires.

Carried by the block 13 is a pair of brackets 22 which extend inwardly toward 75 the block 14, and upwardly toward the ladder. On the free ends of these brackets 22 are mounted the pivotally arranged rock levers 23. At corresponding points on the block 14 are inwardly extending notched 80 members 24, adapted to engage with the lower ends of the rock levers 23, when the blocks are moved into close proximity. Pivotally connected to the upper ends of 85 the rock levers are the lower ends of the lowermost of the central vertical links 25, which are pivotally connected together, as at 26 and centrally to the middle joints of the lazy tongs where they are provided with 90 the rungs 20.

It will be seen that when the screw shaft is turned in one direction, that is to move the blocks toward each other, the lower ends of the rock levers will strike the members 24 and be rocked on their pivots so 95 that the links 25 will also be rocked on their pivots communicating this movement to all of the similar links 25 to the top of the ladder. It will of course, be understood 100 that the links of the lazy tongs are rocked on their pivots to extend the same up into the air, in front of a high building or to an elevated suspended wire.

Attention is called to the fact that when 105 the ladder is in extended position, the rock levers will engage with the members 24, and positively hold the ladder against collapsing. It will also be noted that when the blocks are moved away from each other, the links 25 will be moved to break their 110

joints all the way up the latter, by reason of the fact that the rock levers are carried by the block 13, and move with it.

What is claimed is:

- 5 An extension ladder comprising a pair of lazy tongs, rungs connecting the joints of the lazy tongs and extending therebetween, a support, a longitudinal screw mounted in the support, blocks mounted on the screw and movable toward and away from each other, brackets carried by the blocks and pivotally supporting the lower ends of the lazy tongs, a series of pivotally connected links extending longitudinally through the
- 10 center of each of the lazy tongs, brackets
- 15

carried by one of the sliding blocks, rock arms pivotally mounted on the brackets and each connected at one end to the lower end of each of the last-named links, and means carried by the other block for engagement 20 with the other ends of the rock arms imparting an initial pivotal movement to the said links when the blocks are moved toward or away from each other.

In testimony whereof, I affix my signature, in the presence of two witnesses.

GABRIEL J. KRBAVAC.
